(57) **CLAIM**

The ornamental design for a grill with sawhorse legs and skirt, as shown and described.

DESCRIPTION

FIG. 1 is a top front left perspective view of a grill with sawhorse legs and skirt including my design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right elevation view thereof; and,

FIG. 7 is a left elevation view thereof.

The grill with sawhorse legs and skirt is shown with a symbolic break in its length. The appearance of any portion of the article between the break lines forms no part of the claimed design.

The broken lines are included for the purpose of showing environmental portions of the grill with sawhorse legs and form no part of the claimed design.
